UNITED STATES PATENT OFFICE.

BENJAMIN TOBIAS, OF WASHINGTON, ILLINOIS.

GRADING AND DITCHING MACHINE.

SPECIFICATION forming part of Letters Patent No. 327,740, dated October 6, 1885.

Application filed April 6, 1885. Serial No. 161,292. (No model.)

To all whom it may concern:

Be it known that I, BENJAMIN TOBIAS, of Washington, county of Tazewell, Illinois, have invented a new and Improved Grading and Ditching Machine, of which the following is a full, clear, and exact description.

The invention consists in the construction and arrangement of parts, as will be herein-after fully described, and specifically set forth in the claim.

Reference is to be had to the accompanying drawings, forming part of this specification, in which similar letters of reference indicate corresponding parts in all the figures.

Figure 1 is a side elevation of a grading and ditching machine with my improvement applied, the bucket-wheel being removed; and Fig. 2 is a cross-sectional view showing the knife W and the bucket-wheel in their relative arrangement.

A represents the cart, provided with tilting bottom B, axle E, a plain wheel, F, and a

bucket-wheel, G. On the side of the cart, adjacent to the rear end thereof and to the bucket-wheel, I secure the knife W, which serves to remove any dirt which may extend beyond the inner side of the bucket-wheel. A plow is provided for filling the bucket-wheel, and a lever mechanism is also provided for raising and lowering the same in the usual manner.

Having thus described my invention, I claim as new and desire to secure by Letters Patent—

The combination, with the box A, of the wheels F G, the latter having buckets, and of the knife W, secured to the box at the inner side of the wheel G, substantially as herein shown and described.

BENJAMIN TOBIAS.
